[57] **CLAIM**

The ornamental design for a tool for removing auto doors mounted on roll pins, as shown and described.

DESCRIPTION

FIG. 1 is a front, top and side perspective view of the tool for removing auto doors mounted on roll pins showing our new design;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof; and

FIG. 6 is a bottom plan view thereof.

The broken line showing of the cable is for illustrative purposes only and forms no part of the claimed design.

FIG. 1
